UNITED STATES PATENT OFFICE

ADOLPHUS BARTH, OF ST. PAUL, MINNESOTA.

DUST-COVER FOR BUGGIES.

SPECIFICATION forming part of Letters Patent No. 391,396, dated October 23, 1888.

Application filed July 16, 1888. Serial No. 280,118. (No model.)

To all whom it may concern:

Be it known that I, ADOLPHUS BARTH, a citizen of the United States, residing at St. Paul, in the county of Ramsey and State of Minnesota, have invented certain new and useful Improvements in Dust-Covers for Buggies, of which the following is a specification.

This invention relates to dust-protectors placed over the tops of buggies when they are lowered down; and it consists in the manner of forming and constructing the edges and the holding-straps, as hereinafter shown and described, and specifically pointed out in the claim.

In the drawings, Figure 1 is a perspective view of a buggy-top with one of my improved dust-covers arranged thereon. Fig. 2 is a cross-sectional view of the "bows" on the line X X of Fig. 1. Fig. 3 is an enlarged cross-sectional view about on the line Y Y of Fig. 1, illustrating more fully the construction of the edge of the cover and how it is supported upon the face of the upper or forward bow. Figs. 4 and 5 are enlarged perspective sections 25 of the cover, illustrating modifications in its construction.

A represents the seat, B the top rails, C C' the bows forming the frame for supporting the top, D the leather of the top, and E the "back" 30 of the seat, (shown only in dotted lines in Fig. 1,) all these parts being constructed in the usual manner.

The braces are not shown in the drawings, as they form no part of the present invention, 35 and their presence would cover up and interfere with the clearness of the drawings.

F' represents the dust-protector, which is made of rubber, cloth, leather, or other suitable material, and formed to fit around the 40 edge of the upper bow, C', and cover the seat-back E, and held in place at its forward corners F² by straps F³, which are connected to the corners F² and wrapped around the bows C' and caught over buttons a on the rails B, as 45 shown more clearly in Fig. 2.

The edges of the dust-protector F' are formed

with a cord, b', sewed into it, as shown more clearly in Figs. 4 and 5, to enlarge the edge and cause it to embrace the projecting rim d of the forward or upper bow, C', as shown in Fig. 3, and cling tenaciously thereto. The tighter the cloth forming the body of the cover F' is stretched the more firmly will the edge cling to the bow, and requiring no other fastening than the straps F³.

By this simple device I produce a cover that will not get out of place under any circumstances, and which does not require the insertion of extra buttons or fastenings upon the bows or other parts. The buttons a for the straps F³ are so placed on the rails B as to "draw" the cover forward and stretch it tightly over the bows, and are the same buttons by which the side curtains are secured when the top is raised, requiring, therefore, no extra buttons to secure the dust-cover. The straps also perform an important function in holding the bows down tightly in place, and thus avoid the necessity for additional straps for that purpose.

In Figs. 3 and 5 the edge of the cover F' is shown formed with an extra seam, b², which gives a more finished and symmetrical appearance to the cover, but which does not materially aid in its holding qualities when in operation.

Having thus described my invention, what I claim as new is—

As a new article of manufacture, a dust-cover for buggy-tops, formed of the body F', having cord b' in its edges to embrace the rim of the forward bow, and provided with straps F³, by which the cover may be stretched over the top when the latter is down, substantially as and for the purpose set forth.

In testimony whereof I have hereunto set my hand in the presence of two subscribing witnesses.

ADOLPHUS BARTH.
